UNITED STATES PATENT OFFICE

152,929

DESIGN FOR A HEATER CASING

Carl W. Sundberg and Montgomery Ferar, Detroit, Mich., assignors to Sears, Roebuck and Co., Chicago, Ill., a corporation of New York

Application July 5, 1947, Serial No. 140,106

Term of patent 7 years

(Cl. D81—19)

To all whom it may concern:

Be it known that we, Carl W. Sundberg and Montgomery Ferar, citizens of the United States and residents of Detroit, in the county of Wayne and State of Michigan, have invented a new, original, and ornamental Design for a Heater Casing, of which the following is a specification, reference being had to the accompanying drawing, forming a part thereof.

Fig. 1 is a perspective view of a heater casing, embodying our new design.

Fig. 2 is a fragmentary front elevational view of the same with door in elevated position.

The back of the casing is plain, and the side not shown is substantially similar to the side shown in Fig. 1.

We claim:

The ornamental design for a heater casing, substantially as shown and described.

CARL W. SUNDBERG,
MONTGOMERY FERAR.
